United States Patent Office

Des. 216,308
Patented Dec. 16, 1969

216,308

BLOWGUN

Mahlon E. Hirsch, Fairview, Pa., assignor to Louis Marx
& Co., Inc., a corporation of New York

Filed Feb. 25, 1969, Ser. No. 15,900

Term of patent 14 years

Int. Cl. D22—02

U.S. Cl. D22—3

FIG. 1 is a top plan view of a blowgun embodying my new design;

FIG. 2 is a side elevational view thereof;

FIG. 3 is a bottom plan view thereof;

FIG. 4 is a front elevational view thereof; and

FIG. 5 is a rear elevational view thereof.

I claim:

The ornamental design for a blowgun, as shown.
